US0D1023665S

(12) **United States Design Patent** (10) Patent No.: **US D1,023,665 S**
(45) Date of Patent: ** Apr. 23, 2024

(54) **ELECTRIC HOUSEHOLD DEVICE FOR
MIXING VARIOUS SUBSTANCES**

(71) Applicant: **Capsulab Ltd**, Ramat Gan (IL)
(72) Inventor: **Frank Stephenson**, Flackwell Heath (GB)

(73) Assignee: **Capsulab Ltd**, Ramat Gan (IL)

(**) Term: **15 Years**

(21) Appl. No.: **35/516,251**

(22) Filed: **Feb. 16, 2022**

(80) **Hague Agreement Data**

Int. Filing Date: **Feb. 16, 2022**

Int. Reg. No.: **DM/219621**

Int. Reg. Date: **Feb. 16, 2022**

Int. Reg. Pub. Date: **Feb. 17, 2023**

(57) **CLAIM**

The ornamental design for an electric household device for mixing various substances, as shown and described.

DESCRIPTION

1. Electric household device for mixing various substances

1.1 : Top

1.2 : Bottom

1.3 : Left

1.4 : Front

1.5 : Right

1.6 : Back

1.7 : Perspective

The broken lines shown in the drawings are for illustrative purposes only and form no part of the claimed design.

1 Claim, 7 Drawing Sheets
